UNITED STATES PATENT OFFICE.

HERMAN WOCHER, OF PHILADELPHIA, PENNSYLVANIA.

WINDOW-SASH.

SPECIFICATION forming part of Letters Patent No. 246,266, dated August 23, 1881.

Application filed June 9, 1881. (No model.)

To all whom it may concern:

Be it known that I, HERMAN WOCHER, a citizen of the United States, residing in Philadelphia, Pennsylvania, have invented certain 5 Improvements in Window-Sashes, of which the following is a specification.

The object of my invention is to provide an ordinary window frame and sashes with attachments whereby the sashes may be readily 10 changed from sliding into swinging or pivoted sashes, so that they can be turned around into the room to facilitate cleansing, or when it is desired to expose the entire window-opening for ventilation or other purposes.

15 In the accompanying drawings, Figure 1 is a perspective view of part of the sill and one side of the window-frame furnished with attachments in accordance with my invention; Fig. 2, a perspective view of part of the sill 20 and the opposite side of the window-frame; Fig. 3, a detached view of part of one of the sash-strips of the frame; Fig. 4, a perspective view of the sashes; and Figs. 5, 6, and 7, views of some of the devices which I employ in carrying 25 out my invention.

A represents one side of a window-frame; B, the opposite of the same; D, the base or sill, and E and F the upper and lower sashes, respectively, each of said sashes being hung 30 to the frame by means of cords a a' , connected to balance-weights in the ordinary manner, the weights and pulleys not being shown in the drawings, however, as they form no part of my invention. The cords a a' are secured to 35 the sashes as usual; but the cords a a' are provided at the lower ends with rings b , adapted to hooks b' in recesses in the sashes, so that said cords a a' can be readily applied to or detached from the sashes, for a purpose explained 40 hereinafter.

The side A of the frame has sash-guiding strips d , d' , and d^2 , as usual, and the side B has strips e , e' , and e^2 , the lower portion of the central strip, e' , being cut away for a distance 45 equal to or somewhat in excess of the length of the sash E, and the strip e being furnished with a detachable section, f , of the same length. This section f is held in place by means of a forked plate, f' , and a pin at the top, and by 50 a spring-bolt, f^2 , at the bottom, said spring-bolt being adapted to an opening, f^3 , in the strip e on the base or sill D of the frame.

To the portion A of the frame, between the strips d d' , is secured a plate, g , and to the latter is hinged a plate, g' , which can be turned up so as to occupy a position in line with the plate g , or can be turned outward and downward until it occupies a position at right angles to the said plate g , the hinge being preferably provided with a spring, which will have a tendency to hold the plate g' in the latter position—that is to say, at right angles to the plate g and frame A.

In the plate g' is an opening, i , which, under the circumstances described hereinafter, is 65 adapted for the reception of a pin, i' , at the upper corner of the sash F, the lower corner of the latter having a socket, h , to which is adapted a pin, h' , on the sill D. This pin h' is adapted to a socket, j , in the sill, and is vertically adjustable therein, the pin having projections m , which are adapted to bayonet-slots n in the socket, (see Fig. 7,) so that when the projections are in the deep portions of the slots the head of the pin will be but slightly 70 above the top of the socket j ; but when the projections m occupy positions in the shallow portions of the slots said pin will project considerably above the top of the socket.

To the frame A, between the sash-strips d' 80 and d^2 , is secured a plate, p , similar to the plate g , carrying a hinged plate, p' , in which is formed a slot, s , adapted for the reception of a pin, t , on the upper corner of the sash E, the lower corner of said sash being furnished 85 with a similar pin, which is adapted to a slot, s' , in a bent plate, I, secured to the portion A and sill D of the frame. The pins t are furnished with enlarged heads, and the slots s and s' are enlarged in diameter at the inner ends 90 for the passage of said heads, lateral recesses x being also formed in the slots, for a purpose explained hereinafter.

Under ordinary circumstances the sashes E and F are hung to the cords a a' and slide vertically between the guiding-strips of the frame, as usual, the section f forming a continuation of the strip e , the pin h' being depressed into the socket j , and the plates g' and p' lying snugly against the frame A or fitting into recesses therein, so as not to interfere with the movements of the sashes. If the sashes do not fit loosely enough in the frames to permit them to pass the projecting ears of the hinge- 95 100

plates, said plates should be sunk into the frames to such an extent that the ears will not project therefrom.

When it is desired to swing the sashes into the room the sash F is first raised and the pin *h'* is elevated and retained in an elevated position in the socket *j*. The section *f* of the sash-strip *e* is then removed and the sash lowered until the pin *h'* enters the socket *h* of the sash, the lower edge of the sash being then slightly above the strip *e* of the sill D, and the pin *i'* at the upper corner of the sash being in position for adaptation to the opening *i* of the hinge-plate *g'*, which is caused to engage with said pin by the action of its spring, or if no spring is used the plate may be turned down by hand. The plate *g'* and socket *h*, in connection with the pins *h' i'*, thus form a hinge, on which the sash F is free to swing, the cord *a'* of the sash yielding to permit this swinging movement, until the sash is so far clear of the frame B as to permit the ring *b* to be detached from the hook *b'* of the sash, the ring being then applied to a hook, *w*, on the frame B, so that the cord *a'* is out of the way and does not interfere with the free swinging movement of the sash F.

If it is desired to release the upper sash, E, also from the frame, said sash is pulled down until the pin *t* at the lower corner of the sash enters the enlarged end of the slot *s'* of the plate I, and at the same time the plate *p'* is depressed by its spring or by hand until the pin *t* at the upper corner of the sash E occupies a position in the enlarged end of the slot *s*. The sash E is then turned on the pivot-pins *t*, and at the same time the latter are caused to traverse the slots *s s'* until they rest in the lateral recesses *x*, the sash being supported in this position until the cord *a'* has been detached therefrom and secured to the hook *w* of the frame B, when the sash E is moved so as to draw the pins *t* into the inner ends of the slots, said sash being then free to swing around along-45 side of the sash E.

In restoring the sashes to the frame the above-described operations are reversed.

In carrying out my invention the various hinge-plates, &c., can be readily applied to the window-frame, the integrity of the latter not being interfered with except as regards the cutting away of the sash-guiding strips *ee'*, which does not interfere with the proper guidance of the sashes in their vertical movement. Ready access to all parts of both sashes for cleansing is 55 permitted, and the entire opening of the window-frame can be exposed for ventilation or other purposes.

I claim as my invention—

1. The combination of the window frame and sill, the sash F, having a pin, *i'*, and socket *h*, the pin *h'*, and the hinged plate *g'*, having an opening, *i*, as set forth. 60
2. The combination of the window frame and sash with the socket *j* and a hinge-pin, *h'*, adjustable vertically therein, as set forth. 65
3. The combination of the window frame and sash with the socket *j*, having internal bayonet-slots, *n*, and the pin *h'*, having lugs adapted to said slots, as set forth. 70
4. The combination of the sash F and its hanging devices with the frame B, having a sash-guiding strip, *e*, with detachable section *f*, held in place by a spring-bolt, *f²*, as set forth. 75
5. The combination of the window-frame, the upper sash, E, having pins *t*, the bent plate I, having a slot, *s'*, and the hinged plate *p'*, having a slot, *s*, as set forth. 80
6. The combination of the window-frame, the sash E and its pins, and the plates *i* and *p'*, having slots with lateral recesses *x*, as set forth.

In testimony whereof I have signed my name to this specification in the presence of two subscribing witnesses.

HERMAN WOCHER.
